CELLULOID ARTICLE AND METHOD OF
MAKING SAMECharles R. Keeran, Evanston, Ill., assignor to
Dupont Viscloid Company, Wilmington, Del.,
a corporation of Delaware

Application June 29, 1932, Serial No. 619,868.

3 Claims. (Cl. 18—51)

This invention relates to the treatment of celluloid or like material to form tubular objects, and has for its purpose to provide an improved method of manufacture which permits of the preservation of any design or configuration, such as mottling, inherent in the material. Another object is to produce casings of strip material. Another object of the invention is to provide a method of binding and securing strip material 10 to form a substantially integral tubular casing. A further object is to devise a method that is simple and which permits of economical manufacture. The invention consists in the combination of elements and in the steps of the process 15 of combining them, as herein shown and described, and as indicated by the claims.

In the drawing:

Figure 1 is a somewhat diagrammatic plan view of apparatus for carrying out one phase of 20 my invention.

Figure 2 illustrates a method similar to that of Figure 1, except that the heating means is supplied for the strip material and it is wound on a temporary mandrel.

Figure 3 illustrates a method of binding a plurality of strips of celluloid helically on a mounting member by means of apparatus similar to that shown in Figure 1.

Figure 4 illustrates rather diagrammatically 30 apparatus for carrying out a modification of the process in which the celluloid strips are secured longitudinally to the mounting member.

Figure 5 is a transverse section through the apparatus taken as indicated at line 5—5 on 35 Figure 4.

Figure 6 discloses apparatus for carrying out a further modification of my process.

Figure 7 is a diagrammatic sectional view illustrating the relation of the strips of celluloid to a 40 mounting member just prior to their entry into the heating chamber of the apparatus shown in Figure 6.

Figure 8 is a fragmentary perspective view of a finished tubular member produced by the method employing either the apparatus shown in Figure 4 or that shown in Figure 6.

There are various methods and processes for 50 making tubular casings of celluloid and like material. For example, one inexpensive method is that of extrusion, but by this process any design, configuration or mottling effect in the material is practically destroyed or is altered in a manner which cannot be controlled. An original design or mottling of the material may be retained by a process which consists in first mold-

ing a solid piece, cutting it to a desired size, and then finishing it interiorly and exteriorly, but this method results in a considerable waste of material and consequent increase in cost. I have devised a method for economically making celluloid 5 casings for objects such as pencil barrels, fountain pens and the like, that will ensure the retention of any coloring, design or mottling that may be originally present in the material. It will be seen from the drawing and the following 10 description that my improved method is subject to various modifications, all of which employ the basic principle of utilizing strip material which may be of relatively thin stock. The apparatus is merely shown diagrammatically in the drawing to illustrate a variety of methods by which the process may be carried out.

Figure 1 illustrates the method of winding strip celluloid material helically on a mounting member and shows a reel, 10, of strip material, 11, 20 which is disposed obliquely to the axis of the mounting member, 12, said member being indicated as a tube on which the strip, 11, is wound to form coils, 13, with their marginal edges abutting each other. The angle at which the celluloid strip is fed onto the mounting member as the latter rotates about its axis, is determined by the width of said strip and the diameter of the member, 12. This tubular member, 12, may be of any suitable material, such as metal, composition, paper or celluloid, and when covered by this method is preferably cylindrical. It may be understood that any suitable mechanism will be provided for rotating the mounting member, 12, and simultaneously feeding it in the direction 25 of its axis, as indicated respectively by the arrows, A and B, in the drawing. The surface of the strip celluloid that is to contact with the mounting member is coated with a solvent, such as acetone, applied by a pad or brush, indicated 30 at 14, as it is fed off the reel, 10, so as to render one surface of the strip adhesive for securing to the mounting member, 12. The rotation and longitudinal feed of said member, 12, controls the feeding and winding of the celluloid strip thereon. A roller, 15, may be positioned between the reel, 10, and the mounting member, 12, to engage 35 one edge of the strip, 11, for guiding the latter onto the mounting member and ensuring that the coils shall abut each other. A second roller, 16, is shown with its axis parallel to that of the member, 12, and with its surface engaging the strip, 11, as it contacts with the mounting member so as to press it firmly against the latter to cause 40 its prompt adhesion thereto.

Adjacent the roller, 16, there is mounted a pad or brush, indicated at 17, for applying acetone to the abutting marginal edges of the coils, 13, as they are formed; the acetone, being a solvent for celluloid, softens these marginal portions of the coils, causing the material to flow into any crevices between the coils, and thus fusing them together into an integral tubular casing. This tubular casing is then forced through a final forming die, 18, which may also serve to partially support the same as it is fed longitudinally. The casing may be applied to the tubular mounting member, 12, in any convenient length, and then cut into shorter lengths, if desired, to meet the particular requirements of use. A light finishing coat may be taken off the surface of the tubular casing in a lathe, or similar machine, if desired, so that the final product will appear as though turned from solid stock, the welded or fused connection between the abutting coils being substantially invisible, unless the pattern or configuration of the material itself renders it noticeable.

It may be understood that the celluloid strip material employed in this process is cut from sheets of rolled celluloid and may be formed with certain multi-colored patterns or mottled effects, which serve a decorative purpose, and which are thus retained unimpaired in forming the strip material into a tubular casing by my improved method. And this celluloid strip material may be made quite thin, as there is practically no portion of it to be cut away as waste except in the final finishing cut; and this is particularly true where a mounting member, 12, is employed as the structural support for the decorative celluloid casing.

It will also be evident that if desired the celluloid tubing may be formed of helically wound strip material without including a tubular mounting member as a part of the finished product. For this purpose a temporary mandrel, 12^a, is substituted for the mounting member, 12, as indicated in Figure 2, and instead of applying acetone to the side of the strip which is to form the interior of the tube, the brush, 14, is omitted from the apparatus and a heating element, such as an electric heating coil, 14^b, is disposed adjacent the strip material as it comes off the reel, 10. This heat treatment reduces the resilience of the material temporarily, so that as it is coiled helically on the mandrel, 12^a, and then moves thereon, it takes a permanent "set" with the coils in closely abutting relation. If desired, the acetone may be applied to the abutting edges of the coils on the mandrel, 12^a, as indicated by the position of the brush diagrammatically shown at 17 in Figure 2; but, if preferred, the coil may be permitted to cool completely, and may be removed from the mandrel, 12^a, before the cementing treatment. If handled in relatively short lengths, these lengths may be dipped in the acetone to soften all exposed surfaces, and then permitted to dry, whereupon it will be found that the abutting coils have become fused together. Ordinarily, where no mounting member is to be left in the tubing, the thickness of the strip material will be slightly greater than that which is merely wrapped onto a mounting member, as in the process of Figure 1, but the general principle of the process is the same.

Figure 3 illustrates a method of inter-helically winding two or more strips of celluloid material on a mounting member, 20. The strips, as shown, are of contrasting colors, the strip, 21 being indicated as white, and the strip, 22, as red, and

they are handled by the apparatus as a single strip, being fed parallel to each other onto the mounting member in substantially the same manner as the single strip, 11, is fed onto the mounting member, 12, as shown in Figure 1. It will be evident that three, or even more, strips of contrasting colors may be similarly applied.

Figures 4 and 5 illustrate a modified method of carrying out the process in which the strips of celluloid are secured longitudinally instead of helically. They are shown applied to a mounting member, 25, to form a polyhedral or multi-faced casing, which is illustrated as octagonal. The mounting member, 25, is originally in the form of a cylindrical tube, preferably of celluloid or other material susceptible of deformation. It may be understood that suitable means, not shown, is furnished for feeding the tubing longitudinally. A coating apparatus, indicated at 26, applies acetone or other solvent to the outer surface of said member, 25, as it moves in axial direction. This solvent softens the outer surface of the mounting member, rendering it gummy, adhesive, and in condition to be deformed by the application of pressure. Axially spaced along the mounting member, forwardly of the coating apparatus, 26, are two batteries of four reels each, of celluloid strip material, 27. As shown in the drawing, the reels of one battery are positioned 90 degrees apart, and the reels of the other battery are also spaced 90 degrees apart, but offset 45 degrees with respect to the reels of the first battery, so that strip celluloid may be thus fed onto the mounting member, 25, in eight equiangularly spaced planes, as shown in Figure 4, so as to form an octagonal casing. The celluloid strips may be of any colors or combinations of color, and, as herein shown, and merely by way of illustration, the strip celluloid of the battery of reels positioned further forward in the direction of movement of the tube, 25, is lined to indicate blue. Any suitable design or surface pattern may be formed in the strip material, and will be retained unimpaired in the finished product.

A brush or pad, 28, is positioned for contact with the under surface of each strip as it feeds off the reel, so that these surfaces are coated with acetone to insure adhesion of the strips to the mounting member, 25. Associated with each set of reels I provide pressure rollers, 29, which not only operate to press the strip material against the mounting member, 25, but also exert sufficient pressure to slightly deform the outer surface of the cylinder, 25, flattening it to give the mounting member octagonal cross-section, and to permit the several strips of celluloid to be fitted snugly thereon. When thus fitted, the edges of the strips abut each other, as shown in Figure 7, and the softened surfaces of the strips adjacent these edges are forced together, fusing the strips into an integral enclosing casing for the part 25. The assembled structure is then drawn through a final forming die, 30, to rectify any inaccuracies in its shape. Preferably, for this type of assembly, the lateral edges of the strips may be slightly beveled, so that they shall fit better in their assembled abutting relation and form a closed sharp corner, as seen in Figure 7. This integral tubular member may be made up in any convenient length and then cut into shorter lengths for final use, if desired. Ordinarily, it will require no further finishing of the exterior or interior surface.

Figure 6 illustrates a slight modification of the

process shown in Figures 4 and 5, in that heat is employed for softening the mounting member to permit its deformation. This member is indicated at 35 as being fed longitudinally by any suitable means, not shown, while strip celluloid, 36, is applied to the surface to form any desired number of polygonally related faces. As shown, two batteries of four reels each are provided for supplying the celluloid strips, 36, and these batteries are arranged substantially as in Figure 4, to produce an eight-sided surface. A brush or pad, 37, may be arranged to coat the inner surface of each strip with acetone, or similar solvent, as the material approaches the tubular mounting member, 35, and pressure rollers, 38, are positioned to ensure initial adhesion of the strips. Beyond the rollers, 38, the mounting member with the striping applied is fed through a heating chamber, 39, which softens the material, rendering the cylindrical member, 35, sufficiently ductile so that as it emerges from the heating chamber a set of pressure rollers, 40, arranged in diametrically disposed pairs, will serve to force the strips more firmly onto the mounting member, and at the same time deform the celluloid of the latter to produce a shape similar to that shown in Figure 7. This step is completed by passing the material through the final forming die, 41, corresponding to the die, 30, of Figure 3.

It will be evident that in some instances where the mounting member is of tubular stock, as shown in all the examples illustrated herein, it may be desirable to support such tubular member on a mandrel in order to increase its stability during the application of the strip material to its surface. The provision of such a mandrel

and a means for supporting it are matters well understood by those skilled in the art, and need not be shown or described in detail.

I claim:

1. The method of making a tubular article which consists in winding strip celluloid helically upon a relatively rigid unitary tubular mounting member, with the marginal edges of the strip substantially in abutting contact, uniting said strip with the mounting member, and uniting 10 said edges to form an integral casing for the mounting member; thus to provide a laminated tube with its outer lamination helically wound about an inner lamination in unitary-tube form. 15
2. The method of making a tube from strip celluloid or similar semi-rigid material which method comprises feeding the material with the edges thereof opposed, on to a longitudinally extending support associated with a surrounding forming die for contact with the material, and advancing the support and said material through said forming die, thereby to crowd said edges together face-to-face. 20
3. The method of making a multi-colored tubular article which consists in helically winding two 25 or more strips, arranged edge to edge as fed and of contrasting colored celluloid or like material, onto a relatively rigid unitary tubular mounting member, uniting said strips with the mounting 30 member, and uniting said edges, thus to form an integral casing for the mounting member, thus to provide a laminated article with its outer lamination helically wound about an inner lamination in unitary tubular form. 35

CHARLES R. KEERAN.
